DESIGN FORMING APPARATUS Raymond F. Stockton, Sunland, Calif.
(500 W. Avenue K, Lancaster, Calif.)

Filed Feb. 12, 1957, Ser. No. 639,721

1 Claim. (Cl. 41—10)

This invention relates to design forming apparatus and more particularly to a form thereof adapted for use by children.

The principal object of the invention is to provide a design forming apparatus capable of being arranged and interconnected to form both a primary or underlying design and a second design imposed thereon.

Another object of the invention is to provide a design forming apparatus capable of arrangement to form superimposed designs which also has the capacity of permitting the basic or underlying design to remain undisturbed while the secondary is removed, altered or replaced with another design.

A further object of the invention is to provide a design forming apparatus in which the foregoing objects are realized in practice comprising pluralities of connector elements having at least a pair of holes extending therethrough parallel to each other and parallel to the surface upon which the design is created and at least one other hole extending therethrough parallel to said pair of holes and disposed in a plane more remote from said surface, together with pluralities of rods and other elements having portions thereof receivable in selected ones of said holes in the formation of an infinite variety of designs.

With the foregoing objects in view, together with such other objects and advantages as may hereafter appear, the invention resides in the parts and in the construction, combination and arrangement of parts, described, by way of example, in the following specification of one mode of execution of the invention; reference being had to the accompanying drawings which form a part of said specification and in which drawings:

Fig. 1 is a plan view of certain of the parts of a design forming apparatus embodying the present invention arranged to show how the various parts may be interfitted together.

Fig. 2 is a plan view showing certain of the parts arranged to form a basic or underlying design.

Fig. 3 is a view similar to Fig. 2 but showing the addition of other parts in an overlying design arrangement.

Fig. 4 is a sectional view taken on the staggered line 4—4 of Fig. 3, and

Fig. 5 is an exploded view of the various parts of the design forming apparatus employed in the combinations illustrated in the preceding figures.

Referring first to Fig. 5, the illustrated embodiment of the invention comprises a hanger member 1, having a hole 2 therethrough by which it may be supported by a nail or the like on a wall or other surface and a rod receiving hole 3 disposed below and at right angles to the hole 2, a plurality of connector members 4 and 4' which are identical in side elevation but of different widths; the connector elements 4 and 4' each having a pair of holes 5, 5 disposed one near each end of the member and being parallel to each other and to the base surfaces 6, and a third hole 7 parallel to the holes 5, 5 but disposed midway between them and outwardly from

2

the surfaces 6, 6 a greater distance than the holes 5, 5. The apparatus also includes pluralities of each of two other connectors 8 and 8' which are generally similar in side outline and widths to the connectors 4 and 4', respectively in having pairs of rod receiving holes 9 adjacent the ends thereof in similar location to the holes 5, 5 but having a second pair of holes parallel to and spaced midway between the holes 9, 9' instead of the single hole 7 in the members 4 and 4'.

All of said connector elements are of such thickness that the length of said holes therethrough is at least greater than the diameter of the holes whereby the other design forming elements inserted in said holes, as will be hereinafter described, are held against lateral deflection in said connector elements with resultant stability of the created design. The said first named pairs of holes in all of said connector elements are equally spaced to create a modular dimension in the formation of designs. The rest of the apparatus comprises elements adapted to fit into the holes in the various connector elements and in the example here shown comprises pluralities of straight rods 10, 11, 12 and 13 of varying lengths, other rods 14 with one end thereof bent at right angles offset rods 15 and 16 with parallel, oppositely disposed straight ends laterally offset from each other a distance equal to the spacings of the center holes of connector elements having their ends connected by a rod passing through the end holes thereof and with the end portions thereof being of different lengths as indicated by the end 17 of the rod 16, ring elements 18 having straight ends 19 adapted to be sprung apart to engage one of the holes in a connector element, semicircular elements 20 having straight ends adapted to engage the holes in one side of a pair of connector elements when arranged in spaced end to end relation, U-shaped elements 21 having parallel straight ends of equal length and U-shaped elements 22 having straight ends of unequal length. All of the above elements are provided in sufficient quantities to enable the construction of a wide variety designs and thus there can be provided sets of varying sizes and sets already purchased can be amplified by the mere addition of other quantities of the component parts.

It is to be noted that since the holes 5 of the connectors 4 and 4' and the holes 9 of the connectors 8 and 8' are equally spaced from each other with resultant creation of a modular dimension for a created design in a direction at right angles to the length of the holes, the spacing between like other holes in the connector elements will be spaced from each other either at the said modular distance or a multiple of such modular distance. Where adjacent connector elements are mounted side-by-side on one of the rod-like elements and extend therefrom in opposite directions the central or other intermediate holes therein will be spaced from each other at a distance which is equal to the said modular distance. Where the connector elements are disposed in end-to-end relation but at their adjacent ends are mounted on laterally adjacent rods, these central or other intermediate holes will be spaced from each other a distance which is twice the modular distance. Thus, the offset shown in the members 15 and 16 is equal to the said modular dimension while the end portions of the members 20, 21 and 22 are spaced apart a distance which is twice the modular dimension.

Fig. 1 illustrates manners in which the various elements may be combined with each other. The figure is not intended to show the development of a specific design but only that a series of the longer rods 10 may be connected in parallel spaced modular relation by the connecting elements; some of each of the connecting elements 4, 4', 8 and 8' being thus employed. This figure also illustrates the use of the offset members 15 and 16 showing

3

that the offset dimension is equal to the spacing of the rods 10 achieved by the holes at the ends of the connector elements. The spacing of the end portions of the curved members 20, 21 and 22 is a multiple of the basic modular dimension between adjacent rods 10, it being noted that a pair of the members 20 is shown employed to form a ring engaging two connector members while two of the members 22 are engaged with connector members which are laterally offset from each other.

Referring next to Fig. 2 there is shown the first stage in the development of a completed design comprising the formation of the basic or underlying design. In this illustration, a plurality of long rods 10 have been arranged in spaced modular relation by being arranged in pairs which are slightly alternately laterally offset from each other and with the rods of each pair connected together by spaced connector elements 8 and with the adjacent pairs of rods interconnected by two pairs of the connector elements 4 with one of each pair thereof disposed at opposite sides of the members 8 and the ends of each pair of the rods 10 being connected by connector elements 8. Additionally, the uppermost of the rods 10 carries the hanger 1 by which the design may be suspended while being formed and in line with the hanger, the pairs of rods 10 are connected by connector members 4'. Also, the lowermost rod 10 is also provided with a connector element 4' depending from the mid-length thereof.

Finally in Figs. 3 and 4 the basic design started in Fig. 2 is shown with the embellishment of a second design imposed thereon comprising the addition of short rods 12 to certain of the members 8 connecting the ends of pairs of the rods 10, the addition of rings 18 to the members 8 which are flanked by the connector members 4 and the addition of short rods 11, 12 and 13 to the center holes of the members 4'.

It is obvious that any of the other elements 14, 15, 16, 20, 21 and 22 could be combined with the basic design in an infinite number of ways and it is believed to be equally obvious that the basic design is susceptible of infinite variation. Making the various elements of various colors further increases the possibilities of making different design effects.

It is particularly to be noted that the assembly of the various elements involves only the fitting of the rods and the rod-like end portions of the other elements into selected holes in the connector elements so that the skill required for initial use is only that of a small child. However, the capability of the apparatus to be formed into complex designs is sufficiently great and challenging to make it attractive to older children as well. Moreover, the nature of the interconnection of the parts is such that as it is assembled in any design, the parts stay as-

sembled so that the assembly can proceed without interest being lost due to the parts falling apart at one point while assembly is being made at another point in the design. Still further, the design can be changed and altered while it is being built up when it is desired to make changes in some arrangement or when it is desired to apply a different overlying design on an existing basic design arrangement of the elements.

While in the foregoing specification there has been described a presently preferred embodiment of the invention, it is not to be inferred therefrom that the invention is to be deemed to be limited to the exact details thus disclosed by way of example, and it will be understood that the invention includes all such modifications in the parts, and in the construction, combination and arrangement of parts as shall come within the purview of the appended claim.

I claim:

In a design forming apparatus including pluralities of groups of rod-like design forming elements of different lengths and other pluralities of groups of rod-like elements having different configurations, the combination of a plurality of connector elements effective to interconnect parallel portions of selected ones of said rod-like elements in the formation of plural interconnected designs including at least one design superimposed on another; said connector elements each having a flat surface and having a plurality of parallel, rod receiving holes extending therethrough in lines parallel to said flat surface and parallel to each other, certain of said holes in each of the connector elements being spaced a uniform lesser distance from the plane of said flat surface and certain other of said holes in each of said connector elements being spaced a uniform greater distance from said flat surface whereby said connector elements and said rod-like elements may be combined in a first design based on said first named holes and other rod-like elements combined with said other holes in said connectors in a second design superimposed on said first design; each of said connector elements being in the form of a segmental portion of a torus of rectangular cross section and said rod receiving holes in said connector elements extending only parallel to the axis of generation of the torus.
